US00D934636S

(12) **United States Design Patent** (10) Patent No.: **US D934,636 S**
Munie et al. (45) Date of Patent: **** Nov. 2, 2021**

(54) **INSULATING DEVICE**(71) Applicant: **YETI Coolers, LLC**, Austin, TX (US)(72) Inventors: **Jeffrey Charles Munie**, Austin, TX (US); **Kyle Edward Rogers**, Austin, TX (US); **Donald Edward Desroches**, Austin, TX (US); **John Loudenslager**, Austin, TX (US); **Derek G. Sullivan**, Austin, TX (US); **Alex Baires**, Austin, TX (US)(73) Assignee: **YETI Coolers, LLC**, Austin, TX (US)(**) Term: **15 Years**(21) Appl. No.: **29/765,079**(22) Filed: **Jan. 5, 2021****Related U.S. Application Data**

(60) Continuation of application No. 16/934,865, filed on Jul. 21, 2020, which is a continuation of application No. 15/845,737, filed on Dec. 18, 2017, now Pat. No. 10,781,028, which is a continuation-in-part of application No. 15/451,064, filed on Mar. 6, 2017, now Pat. No. 10,143,282, which is a continuation-in-part of application No. 15/261,407, filed on Sep. 9, 2016, now Pat. No. 10,384,855, which is a continuation-in-part of application No. 15/154,626, filed on May 13, 2016, now Pat. No. 10,029,842, which is a continuation-in-part of application No. 14/831,641, filed on Aug. 20, 2015, now Pat. No. 9,796,517, which is a division of application No. 14/479,607, filed on Sep. 8, 2014, now Pat. No. 9,139,352.
